Geo. P. Kimmel ATTORNEY.

UNITED STATES PATENT OFFICE.

ARCHIE S. AVERY, OF TWO RIVERS, WISCONSIN.

BAND-SAW DRESSER.

Application filed November 4, 1926. Serial No. 146,243.

This invention relates to a band-saw dresser, and has for its object to improve and simplify the construction and operation of tools of the character referred to so as to be reliable and efficient in its use, comparatively inexpensive to manufacture, conveniently operated, and so designed that the jointing or evening of the saw teeth is accomplished automatically as the saw is moved through the tool.

With the foregoing and other objects in view, the invention consists of the novel construction, combination and arrangement of parts as hereinafter more specifically described, and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:

Fig. 1 is a top plan view of a band-saw dresser, in accordance with this invention, and showing the adaptation thereof in connection with a saw.

Fig. 2 is a section on line 2—2 of Fig. 1.

Fig. 3 is a front elevation of the device.

Fig. 4 is a section on line 4—4 Fig. 2.

A band saw dresser, in accordance with this invention, hereinafter termed a tool comprises a rectangular body portion 1 having extended from its inner face 2, a right angular extension 3, which is flush with one end of the body portion 1. The extension 3 is of the same width as the width of the body portion 1. The thickness of the extension 3 is of less than half the length of the body portion 1. Preferably the height of the extension 3 is greater than the height of the body portion 1. The inner face of the body portion, from that end free of the extension 3 to the latter and at each side marginal portion thereof, is formed with a rabbet 4 having its inner end terminating at the inner face of the extension 3. Each rabbet 4 provides a seat and the forming of the inner face of the body portion 1, with the rabbets 4, provides a tongue 5 which extends lengthwise of said body portion 1.

The body portion 1 is further formed with a lengthwise disposed socket 6, having a threaded wall and which opens at that end of the body portion 1 opposite the end provided with the extension 3. That end of

the body portion 1 opposite the end provided with the extension 3 is formed with a countersunk portion 7 which surrounds the outer end of the socket 6. The socket 6 is of less length than the length of that part of the body portion 1 which is free of the extension 3. The body portion 1, at a point between the inner end of the socket 6 and the inner face of the extension 3, or rather at a point between the inner end of the socket 6 and the transverse median of the body portion 1, is provided with a socket 8, which is disposed at right angles to the socket 6 and opens at the inner face 2 of the body portion 1. The wall of the socket 8 is threaded.

The inner face of the extension 3 is incut to provide a lengthwise extending groove 9 which is coextensive with said inner face, and has its upper wall positioned in proximity to the top of the extension 3 and its lower wall in close proximity to the point of joinder of the extension 3 with the body portion 1. Mounted in the groove 9, as well as being of the same width and length as said groove 9, is a file 10. The extension 3 is provided with a plurality of binding screws 11 for fixedly securing the file 10 within the groove 9.

Slidably mounted on the body portion 1, is a carrier 12 and which comprises a body portion 13 having its length the same as the width of the body portion 1, and said body portion 13 has its inner face formed with a groove 14 for the reception of the tongue 5. The ends of the body portion 13 are flush with the sides of the body portion 1. The inner face of the body portion 13, is formed with a groove 15 which extends from end to end thereof, and has its top wall positioned in proximity to the outer face of the carrier 15 and its bottom wall arranged in proximity to the inner face of the carrier 13. The groove 15 is coextensive with the inner face of the carrier 15 and is adapted to have mounted therein a file 16, which opposes the file 10. The file 16 is coextensive with the groove 15 and the carrier 12 is provided with binding screws 17 for fixedly securing the file 16 within the groove 15.

The carrier 12 between its longitudinal median and its inner face thereof is formed with an oblong opening 18 which extends from the outer to the inner face of the carrier 12. The outer part of the opening 18,

is of greater size than the remaining part thereof, and that part of the opening 18 of greater size is indicated at 19. The socket 8 is cylindrical and registers with the inner 5 end of the oblong opening 18.

The carrier 12, intermediate its outer and inner faces, is formed with a transversely extending opening 20 which communicates at its inner end with the opening 18 and at its 10 outer end opens at the outer side face of the carrier 12. The wall of the opening 20, at the outer terminal portion thereof is provided with threads 21. Slidably mounted in the opening 20 is a spring controlled plunger 15 22, having a reduced shank 23. Engaging with the threads 21, is an abutment 24 positioned in the outer portion of the opening 20 and interposed between the abutment 24 and the plunger 22 is a coiled spring 25, or 20 rather the controlling spring 25 for the plunger 22. The spring 25 surrounds the reduced shank 23 of the plunger. The plunger 22, spring 25 and abutment 24 constitutes 25 means for shifting the carrier 12 outwardly, when the latter is released in a manner to be presently referred to.

Extending through the opening 18 and engaging with the threaded wall of the socket 8 is a headed screw 26 and the head thereof 30 is indicated at 27, and which is positioned in the enlarged portion of the opening 18. The shank of the screw 26, extends through the smaller portion of the opening 18. The plunger 22 abuts against the shank of the 35 screw 26, and when in such position the tension of the spring 25 is increased. The carrier 12 is locked from shifting, with respect to the body portion 1, by a threaded retaining member 28, which is in the form of a 40 threaded shank, provided with a disk like head 28 of greater diameter than the shank and with the head 29 formed with a wing piece 30 to facilitate the shifting of the member 28. The head 29 overlaps the carrier 12 and when it bears against said carrier 12, the latter is prevented from being shifted by 45 the spring 25. When the member 28 is withdrawn from the socket 6, said member having threaded engagement with the wall of 50 the socket 6, the carrier 12 will be shifted outwardly on the body portion 1 due to the action of the spring 25 in connection with the plunger 22 and with the latter abutting against the shank of the screw 26.

The saw is indicated at 31 and is interposed between the files 10 and 16, see Figures 55 1 and 2. When the carrier 12 is shifted outwardly with respect to the body portion, the saw 31 can be readily positioned between the files 10 and 15.

When using the tool, the saw is positioned on a bench with teeth pointing upward and backward, after which the tool is adjusted for the purpose of mounting in it the saw. 60

When the tool is mounted on the saw, the

carrier 12 is latched or locked to prevent the outward shifting thereof on the body portion 1. When the tool has been positioned on the saw, the latter is marked at the starting point thereon and the saw is pulled around through the tool with the teeth pointing backward, the opposite direction from which the saw runs, and when the saw is pulled around to the mark, the carrier is closed a little more with respect to the saw 75 and the operation is repeated about three or four times until the desired result is obtained. The saw is then sharpened in the usual way and is then ready for smooth sawing. 80

It is thought that the many advantages of a tool in accordance with this invention, can be readily understood, and although the preferred embodiment of the invention is as illustrated and described, yet it is to be 85 understood that changes in the details of construction can be had which will fall within the scope of the invention as claimed.

What I claim is:

1. A tool for the purpose set forth comprising a body portion formed at one end with a right-angular extension having its inner face provided with a file member receiving groove, a spring controlled adjustable carrier, slidably connected to and upon said body portion and opposing said extension and having its inner face formed with a file member receiving groove opposing the groove in said extension, and means carried by the body portion to provide for the adjusting of the carrier against the action of its controlling spring and relative to the extension. 90

2. A tool for the purpose set forth in accordance with claim 1, file member securing means carried by the inner end of said carrier and the free end of said extension. 105

3. A tool for the purpose set forth in accordance with claim 1, removable file member securing means detachably engaging with the inner end of said carrier and free end of said extension and projecting into said groove. 110

4. A tool for the purpose set forth comprising a body portion formed at one end with a right-angular extension having its inner face provided with a file member receiving groove, a carrier slidably mounted on said body portion, and formed with an oval shaped opening, means extending through said opening, engaging the wall thereof and fixedly secured to the body portion for slidably connecting the carrier to the body portion, spring controlling means for and mounted in the carrier and abutting against the means for slidably connecting the carrier to the body portion, said carrier having its inner face formed with a file member receiving groove opposing the groove formed in said extension, and means connected to 115 120 125 130

the body portion and overlapping the carrier to provide for the adjusting of the latter relative to the extension against the action of the spring controlled means for the carrier.

5. A tool for the purpose set forth, in accordance with claim 4, removable means carried by the free end of the extension and inner end of the carrier for detachably securing file members within said grooves.

6. A tool for the purpose set forth comprising a pair of opposed normally spaced file members, a body portion having an extension providing a stationary supporting means for one of said members, an adjustable spring controlled carrier for the other of said members, said carrier slidably connected upon said body portion, and means carried by said body portion and abutting said carrier to provide for the adjusting of the latter against the action of the controlling spring therefor.

7. A tool for the purpose set forth in accordance with claim 6, a screw element loosely extended through and abutting said carrier and threadably engaging in said body portion for slidably connecting the carrier to said body portion.

8. A tool for the purpose set forth comprising a body portion having an extension to provide a stationary support for a file member, an adjustable spring controlled slideable carrier having means for supporting a file member in opposed relation with respect to the file member supported by said extension, said carrier positioned on said body portion, means extending through the carrier and fixed to said body portion for slidably connecting the carrier thereto, a spring controlled means for the carrier mounted therein and abutting against the means for slidably connecting the carrier to the body portion, and means adjustably connected to the body portion and overlapping said carrier to provide for adjusting the latter against the action of the spring controlled means therefor.

9. A tool for the purpose set forth comprising a body portion having an extension to provide a stationary support for a file member, an adjustable spring controlled slideable carrier having means for supporting a file member in opposed relation with respect to the file member supported by said extension, said carrier positioned on said body portion, means extending through the carrier and fixed to said body portion for slidably connecting the carrier thereto, a spring controlled means for the carrier mounted

therin and abutting against the means for slidably connecting the carrier to the body portion, means adjustably connected to the body portion and overlapping said carrier to provide for adjusting the latter against the action of the spring controlled means therefor, and said body portion and carrier having coacting means to provide a guide for the sliding movement of the carrier.

10. A tool for the purpose set forth comprising a body portion having an extension to provide a stationary support for a file member, an adjustable spring controlled slideable carrier having means for supporting a file member in opposed relation with respect to the file member supported by said extension, said carrier positioned on said body portion, means extending through the carrier and fixed to said body portion for slidably connecting the carrier thereto, a spring controlled means for the carrier mounted therein and abutting against the means for slidably connecting the carrier to the body portion, means adjustably connected to the body portion and overlapping said carrier to provide for adjusting the latter against the action of the spring controlled means therefor, and means carried by the free end of the extension and the inner end of the carrier for detachably securing the file members therewith.

11. A tool for the purpose set forth comprising a body portion having an extension to provide a stationary support for a file member, an adjustable spring controlled slideable carrier having means for supporting a file member in opposed relation with respect to the file member supported by said extension, said carrier positioned on said body portion, means extending through the carrier and fixed to said body portion for slidably connecting the carrier thereto, a spring controlled means for the carrier mounted therein and abutting against the means for slidably connecting the carrier to the body portion, means adjustably connected to the body portion and overlapping said carrier to provide for adjusting the latter against the action of the spring controlled means therefor, means carried by the free end of the extension and the inner end of the carrier for detachably securing the file members therewith, and said carrier and body portion having coacting means to provide a guide for the sliding movement of the carrier.

In testimony whereof, I affix my signature hereto.

ARCHIE S. AVERY.
